Specification of Letters Patent.

Patented May 12, 1914.

Application filed February 19, 1913. Serial No. 749,312.

To all whom it may concern:

Be it known that I, HENRY B. FEBIGER, a citizen of the United States, residing in the city of New Orleans, parish of Orleans, 5 State of Louisiana, have invented a new and useful Automatic Shotgun, of which the following is a specification.

My invention consists of an automatic shot-gun in which the recoil of the barrel 10 and breech-block sets the firing pin and causes the exploded shell to be ejected and a fresh cartridge to be fed from the magazine.

It further consists of an improved sear 15 and trigger mechanism in such gun.

It further consists of improved means for holding the breech-block in its recoiled position until the barrel has returned to normal position, the exploded shell has been 20 ejected, and a fresh cartridge has been fed.

It further consists of improved means for connecting and disconnecting the breech-block and barrel.

It further consists of improved means for 25 feeding the cartridges from the magazine.

It further consists of improved means for stopping the successive cartridges in the magazine as each is fed to the feeder, and for successively releasing them.

30 It further consists of improved means for feeding the cartridges to the receiver.

It further consists of improved means for locking the barrel to the breech-block during the recoil of the latter.

35 It further consists of improved means for withdrawing the firing-pin.

It further consists of other novel features of construction, all as will be hereinafter fully set forth.

40 The annexed drawings and the following description set forth in detail one mechanical form embodying the invention, such detail construction being but one of various mechanical forms in which the principle of 45 the invention may be used.

In said annexed drawings Figure 1 represents a longitudinal section of my improved fire-arm, illustrating the parts thereof in position ready for firing. Fig. 2 represents 50 a longitudinal section of the fire-arm after firing and with the barrel and breech-block recoiled. Fig. 3 represents a longitudinal section of the fire-arm with the parts in feeding position. Fig. 4 represents a longitudinal section of the fire-arm, illustrating 55

the breech-block and carrier in elevation. Fig. 5 represents a longitudinal section illustrating said parts as seen from the left-hand side of the fire-arm. Fig. 6 represents a longitudinal horizontal section taken on the line $x-x$ in Fig. 1. Fig. 7 represents a longitudinal horizontal section on the line $y-y$ in Fig. 4. Fig. 8 represents a side-elevation of the fire-arm. Fig. 9 represents a side-elevation of a part of the barrel and an axial section of the fore-arm and magazine. Fig. 10 represents a sectional detail view of the outer end of the fore-arm and magazine. Fig. 11 represents a transverse section of the plug for the forward end of the magazine. Fig. 12 represents a top plan view of the breech-block. Fig. 13 represents a side elevation of the barrel-extension. Fig. 14 represents a perspective detail view of the sliding stop for the breech-block. Fig. 15 represents a transverse section on the line $z-z$ in Fig. 1. Fig. 16 represents a transverse section on the line $a-a$ in Fig. 1. Fig. 17 represents a transverse section on the line $b-b$ in Fig. 1. Fig. 18 represents a transverse section of one-half of the receiver on the line $c-c$ in Fig. 1. Fig. 19 represents a front-end view of the receiver. Fig. 20 represents a part section and part side-elevation of the receiver and the ends of the barrel and magazine. Fig. 21 represents a longitudinal horizontal section on the line $y-y$ in Fig. 4, showing the magazine empty. Fig. 22 represents a top-plan view of a portion of the barrel extension and of the breech-block. 90

Similar numerals of reference indicate corresponding parts in the figures.

Referring to the drawings, the reference numeral 1 indicates the stock of the fire-arm, to which a receiver, 2, comprising a top, 147, of substantially cylindrical outline, flat side-walls, 148, and a forward wall or block, 70, and having tangs, 3 and 4, is secured, all of which parts are formed from one integral piece of metal. A trigger and sear frame, 5, having a trigger-guard, 6, and longitudinal flanges, 7, is secured between the side-walls of said receiver, being inserted through the open bottom of the same. A trigger, 8, is pivoted between said flanges and has a rearwardly projecting lug, 9, to which a post, 10, is pivotally connected, which post slides in a bearing, 11, between the flanges and has a spring, 12, 100 105 110

which tends to throw the trigger forward. The upper portion of the trigger has a forwardly projecting arm, 13, formed with a longitudinal bore, 14, having a slot, 15, in the upper side of its forward end. A plunger, 16, slides in said bore and bears against a spring, 17, within the same, and the forward end of said plunger has a web, 18, slidible in said slot and projecting to engage and be stopped by a pin, 19, secured between the flanges. The forward end of the plunger has a nose, 20, projecting beyond the forward end of the arm of the trigger. A sear, 21, slides with a nearly vertical slot, 22, upon a pin, 23, between the flanges, and has a sear-shoulder, 24, upon its upper edge, and a shoulder, 25, upon its rear edge, which shoulder may be engaged by the nose upon the spring-plunger in the trigger-arm. A pin, 26, extends from the lower edge of the sear and slides in a bore, 27, in the trigger-frame, and a spring, 28, is coiled around said pin to force the sear upward.

25 The barrel, 29, has its rear, reduced and screw-threaded end secured in a threaded socket, 30, in the forward end of a barrel-extension, 31, having a sliding fit within the upper portion of the receiver and having its bottom, right-hand side and rear end open. A breech-block, 32, has a sliding fit in said extension and in the receiver, having foot-flanges, 33 and 34, sliding upon a shoulder, 35, and in a groove, 36, respectively, in the side-walls of the receiver. The rear end of the breech-block is formed with ears, 37, between which the forked forward end, 38, of a main-spring rod, 39, is pivoted upon a pin, 40, and the rear end of said rod bears against a piston, 41, sliding in a tube, 42, in the stock of the gun and bearing against a main-spring, 43, confined in said tube. The forward end of said main-spring tube is secured in an enlargement, 44, upon the upper tang, and the rear end of the tube is secured in the foot of the stock, so that said tube serves as a fastening for the receiver to the stock, and the lower tang is secured to the stock by a screw, 45, passing through the stock and into said enlargement of the upper tang. The breech-block is formed with an oblique bore, 46, extending from the lower rear corner to the center of the front-face, and the forward end of said bore is contracted to form a stop for a shoulder, 47, at the reduced forward end of a firing-pin, 48, having play in said bore. A firing-spring, 49, is coiled around the firing-pin and bears against a rearwardly-facing shoulder, 50, upon the pin, and against a threaded collar, 51, in the bore, to throw the pin forward. The rear end, 52, of the firing pin is preferably flat or polygonal to slide in the correspondingly shaped rear portion of the bore, and has a forwardly-facing

55 60 65 70 75 80 85 90 95 100 105 110 115 120 125 130

sear-shoulder, 53, which engages the upper shoulder of the sear when the breech-block is thrown forward. A longitudinal bore, 54, is formed in the upper part of the breech-block, and a bolt, 55, is journaled to rock in said bore and has two oblique flanges, 56, upon its rear portion, which flanges will be engaged by the ends of two fingers, 57, in the closed rear end of the receiver when the breech-block is thrown rearward, thereby giving the bolt a one-quarter turn. A torsion-spring, 58, has one end secured to the forward end of the bolt and its other end secured to a screw-plug, 59, in the forward end of the bore, to reverse the twist of the bolt when the latter is released from the fingers. A locking-screw, 60, secures the screw-plug against turning under the torsional strain of the spring. The bore of the breech-block has an enlargement, 61, opening through the top of the same, and the inner face of the top of the barrel-extension has a recess, 62, which registers with the opening of said enlargement when the breech-block is fully within the barrel-extension with its forward end closing the chamber in the barrel. An eccentric block, 63, upon the rotary bolt fits to be turned into and out of engagement with the recess in the barrel-extension, when such recess registers with the opening of the enlargement in the breech-block, whereby such breech-block and extension may be locked together and unlocked by rotating the bolt. A cam-lug, 64, projects laterally from the eccentric block and through an opening, 65, in the enlargement of the bore for the bolt, into the bore for the firing-pin to engage a forwardly facing shoulder, 66, upon said pin, whereby the latter will be slightly withdrawn when the bolt is rotated, to draw its forward end into the bore. The eccentric block has an oblique shoulder, 146, and the rear end of the barrel extension has an oblique edge, 147, which will engage such oblique shoulder when the breech-block moves forward to turn the rotary bolt and permit the eccentric block to be turned and pass beneath the extension as the breech-block moves forward.

55 60 65 70 75 80 85 90 95 100 105 110 115 120 125 130

A magazine-tube, 67, has its threaded rear end, 68, screwed into an opening, 69, in the forward wall or block, 70, of the receiver. A spool-shaped plunger or follower, 71, is slidible within said tube and has the rear end of a coil-spring, 72, bearing within a socket, 73, in the forward end of the plunger. The forward end of said spring bears against a plug, 74, secured in the forward end of the tube. Said plug has a diametrical slot, 75, within which a longitudinally slotted shank, 76, of a finger-piece, 77, slides upon a pin, 78, passed through the plug at right angles to the slot. The forward portion of the slot in the plug extends through the sides of the same, and the tube has cor-

responding slots, 79, in its end, so that the finger-piece can be drawn out and turned at a right angle upon the pin to have its shank engage the slots in the tube, as indicated in dotted lines in Fig. 10 of the drawings, when the tube may be turned to screw its rear end into or out of the threaded opening in the receiver. A fore-arm, 80, has the smaller forward portion, 81, of its bore fitted upon the tube and its rear end secured in the front-block of the receiver by a tongue-and-groove connection, 82. A collar, 83, is secured upon the forward end of the tube by means of screws, 84, movable in slots in the tube against which the plug bears and bears against the forward end of the fore-arm, thus securing the latter to the tube. A collar-bracket, 85, is secured upon the under side of the barrel to be slidable upon the tube and within a large rear portion, 86, of the bore in the fore-arm, and a coiled action-spring, 87, coiled upon the tube, has its forward end bearing against the slideable collar, and its rear end bearing against a rigid collar, 88, upon the tube.

A carrier comprises a longitudinally slotted arm, 89, having a headed finger-piece or stop, 90, sliding in its slot, and extending forwardly from a yoke, 91, having a rearwardly extending long arm, 92, and a rearwardly extending short arm, 93, at its ends and fulcrumed upon a pin, 94, secured through the forward ends of the flanges of the trigger-frame. The forward end of the slotted arm extends to near the rear end of the magazine-tube. A cam-arm, 95, carrying a roller, 96, in its outer end, is pivoted upon the rear end of the long actuating arm 92 of the carrier, and the inner end of said cam-arm has a cam-surface, 97, which bears against a spring-bolt, 98, in a bore in said actuating arm and having a spring, 99, forcing it rearward. The short arm of the carrier has a shoulder, 100, upon its lower edge, against which bears an upwardly acting spring, 101, so that the normal tendency of the carrier is to have its slotted forward arm tilted downward, while said spring is weaker than the spring within the arm. The inner face of the left-hand wall of the carrier-chamber, 102, in the receiver, has an undercut recess, 103, at its rear edge, in which slides a locking-bolt, 104, having a spring, 105, forcing it upward, and formed upon its upper end with a hump, 106, or cam inclined forward and rearward, and with a rearwardly facing shoulder, 107, which engages a notch, 108, in the forward end of the under side of the breech-block. A cam-bulge, 109, is formed upon the rear end of the lower edge of the barrel-extension to depress the hump and locking-bolt when the barrel is moved forward after recoil. The inner face of the right-hand wall of the carrier-chamber has an undercut recess, 110, at

its forward edge, in which slides a flat bolt, 111, having a spring, 112, forcing it upward, and formed upon its upper edge with a rearwardly facing, steeply inclined cam-shoulder, 113, which is engaged and depressed, when the breech-block is in its forward position, by a cam-lug, 114, projecting downward from the side of said block. The inner face of said bolt has a stop-lug, 115, at its forward edge, which lug will project inward, a short distance across the rear end of the magazine tube, when the bolt is in its upper position, to stop rearward movement of the cartridge in the magazine, and leave such end unobstructed when the bolt is depressed.

A lever, 116, is fulcrumed within the right-hand wall of the receiver to rock laterally, and the forward end, 117, of said lever is bent inward to project into the rear end of the magazine, and has its widened inner end inclined in opposite directions. The rear arm of this lever is inwardly inclined, and the rear end, 145, is bent upward to engage a notch, 146, in a pin, 118, transversely 90 slidable and rocking in the sides of the receiver. Said notch is of sufficient depth to admit of the pin rocking and of the end of the arm engaging it. A spring, 119, bears against a shoulder upon the pin and is connected to the pin and the wall of the receiver, so as to normally push the pin to the right and at the same time exert torsion upon the pin. A stop or pawl, 120, projects upward and rearward from the pin to engage a notch, 121, in the under side of the breech-block when the pin and pawl are moved to their extreme right-hand position by the spring, when the lever is free to rock by the inwardly bent forward end of the latter being free to enter the rear end of the magazine when the latter is empty or the spool-shaped plunger or follower is opposite said cam-shaped inward end, as shown in Fig. 21. The right-hand end of the transversely sliding pin projects beyond the outer face of the wall of the receiver to admit of the pin being shifted by pressure upon the projecting end.

A stop-lever, 122, is pivoted in a recess, 123, in the inner face of the left-hand wall of the carrier-chamber, and has a spring, 124, bearing against its rear arm, normally holding said lever flush with the face of the wall, and the forward arm of said lever has a stud or button, 125, extending through the wall of the chamber to admit of the forward arm of the stop-lever being projected into the carrier-chamber.

A spring-actuated hooked extractor, 126, 125 is pivotally mounted in a groove, 127, in the forward end of the right side of the breech-block to enter the chamber of the barrel and engage the rim of the cartridge, so as to extract the shell as the breech-block recoils. 130

A longitudinal groove, 128, is formed in the inner face of the side of the barrel-extension, and has an enlargement, 129, and a spring-ejector, 130, is secured with its head, 131, in such enlargement, and has a forwardly-facing shoulder, 132, at its free rear end. The left-hand side of the breech-block has a groove, 133, to admit of said shoulder projecting beyond the face of the wall.

10 The forwardly extending arm of the trigger is formed with a shoulder, 134, at the inner end of its under side, and with a notch, 135, adjoining said shoulder. A safety-catch is formed by a slide, 136, longitudinally slideable over a slot, 137, in the trigger-frame and having an upwardly projecting lug, 138, upon its rear end and a finger-piece, 139, sliding in the slot. When the slide is moved to bring its lug beneath the shoulder of the trigger-arm, the trigger cannot be pulled, and when the slide is moved to bring its lug to register with the notch in the trigger-arm, the trigger may be pulled. The upper side of the slide has two notches, 140, which are engaged by the end of a spring, 141, so that the catch may be held in safety or free position. The right side-wall of the carrier chamber has an ejection-opening, 142, with which the open side of the barrel-extension registers when in forward position. The trigger and sear frame is secured in the receiver by a screw, 143, and the bolt 94, upon which the carrier is fulcrumed.

15 20 25 30 35 40 45 50 55 60 65 In practice, when the magazine is to be loaded, the shells, 144, are inserted through the open bottom of the carrier-chamber, pushing the slotted carrier-arm upward, and are pushed into the rear end of the magazine, each shell pushing the plunger forward in the magazine. The stop-lever is pushed inward by its button as each shell is inserted, to stop the shell from being again pushed out by the magazine-spring. As soon as the loading is finished, the slotted carrier-arm flies downward, and the last-inserted shell is forced rearward with its head bearing against the sliding stop in the slotted carrier arm. When now the barrel is pushed rearward, it will move the breech-block with it and release the bolt or cartridge-stop carrying the lug, so that such stop may move upward, bringing the lug upon the same into the path of the succeeding cartridge and preventing the same from entering the carrier-chamber. The barrel is now pushed rearward, carrying the breech-block with it, and when the breech-block arrives at its rearmost position, the shoulder upon the locking-bolt will move upward and engage the notch in the forward end of the breech-block and retain it in such position. The rearward movement of the breech-block will tilt the cam-arm upon the long arm of the carrier rearward, placing the spring-

70 75 80 85 90 95 100 105 110 115 120 125 130 bolt in said latter arm under tension. When the barrel is again allowed to be drawn forward by the action-spring, the spring-bolt will tilt the carrier to raise the slotted arm and the cartridge, to bring the forward end of the same in register with the chamber of the barrel and its head in line with the forward end of the breech-block, as seen in Fig. 3 of the drawings. When the barrel and its extension arrive at the forward end of their movement, the cam-bulge upon the barrel extension will bear against the hump upon the locking-bolt and depress the same, disengaging its shoulder from the notch in the breech-block and allowing the latter to move forward under the action of the main-spring. The forward movement of the breech-block straightens the cartridge and carries it forward into the chamber of the barrel, as seen in Fig. 1. The rearward movement of the barrel and breech-block caused the rear end of the rotary locking-bolt in the latter to have its oblique flanges engage the fingers in the rear end of the receiver to be rotated, thus bringing the eccentric block upon the rod out of engagement with the recess in the barrel-extension to allow the barrel and extension to be moved forward by the action-spring without moving the breech-block and, at the same time, allowing the cam-lug upon said block to engage the shoulder upon the firing-pin to draw the latter partly into its bore, so that its projecting end shall not strike the fulminating cap of the cartridge when the breech-block moves forward. When the breech-block moves forward and the oblique flanges upon the rotary bolt are released from the fingers, the oblique edge of the barrel extension engages the oblique shoulder of the eccentric block upon the rotary bolt and keeps the same turned so that the breech-block may pass into the barrel-extension. As the breech-block moves forward, the sear-shoulder upon the firing-pin engages the shoulder of the sear, drawing such pin into the block as the latter moves forward. When said block arrives within the barrel-extension, the torsion spring will rotate the rotary bolt to turn the eccentric block into the recess in the breech-extension and to disengage its cam-lug from the firing-pin. When during these movements the breech-block arrived at its foremost position, the cam-lug upon its forward end depressed the locking-bolt in the forward end of the carrier-chamber and allowed another cartridge to be fed onto the carrier-arm, which tilted down as soon as the breech-block released the cam-arm at the rear end of the carrier. When the trigger is pulled, it will pull down the sear and release the firing-pin, whose spring will drive it forward to strike the fulminating cap, exploding the cartridge. The recoil of the explosion will recoil the

breech-block and, the latter being locked with the barrel extension, the barrel and extension will also recoil, and the above-described action will be repeated, with the 5 addition that, as there now is an empty shell in the chamber, the extractor will pull the latter out of the chamber when the barrel travels forward and the shoulder of the ejector in the extension will tilt such shell 10 when it strikes the head of the latter, and eject it through the ejection-opening, whereupon a fresh cartridge is fed and the operation may be repeated. As the plunger in the arm of the trigger is drawn inward by the 15 web upon the same engaging the pin 19, and its nose is consequently disengaged from the shoulder 25 upon the sear, when the trigger is fully pulled, the sear can again move upward in position to engage the shoulder upon 20 the firing-pin while the trigger is yet held pulled. When the last cartridge in the magazine has been fed, the spool-shaped follower moves into the carrier-chamber, and the inwardly projecting cam-end of the stop- 25 lever 116 is forced inward, the lever is rocked, and the transverse pin is moved to the right by its spring, placing the pawl thereon in the path of the notch in the under side of the breech-block. When the breech-block recoils at the next fire, the pawl will 30 engage the notch in the breech-block and stop the same in its rear position while the barrel and extension will move forward, ejecting the empty shell. New cartridges 35 may now be charged into the magazine through the open bottom of the carrier-chamber, the finger-operated stop-lever 122 preventing the magazine-spring from forcing the cartridge back, until the magazine is 40 fully charged, when the gun is again ready for action. The cartridges in the rear end of the magazine keep the pawl in inoperative position by bearing against the cam-edge of the inturned end of the lever 116, and it is 45 only when the magazine is empty that the pawl is in operative position and holds the breech-block in its rear position, from which it may be released by pressing inward against the spring upon the projecting end 50 of the transversely movable pin. If it is desired to fire the last cartridge before reloading the magazine, the pin 118 may be pressed to release the breech-block. Otherwise, in reloading, the first cartridge loaded 55 into the magazine releases the breech-block to drive the remaining cartridge in the carrier into the chamber. A cartridge may be forced from the carrier into the chamber of the barrel by means of the finger-piece sliding 60 in the slotted arm, so that an extra cartridge may be fed into the magazine.

The gun may be taken down by pulling out the finger-piece at the forward end of the magazine and tilting it laterally, when 65 the magazine can be unscrewed by the same

from the receiver and removed together with the fore-arm and the barrel and extension. The trigger and sear frame may be removed from the receiver by unscrewing the fastening-screws, and the breech-block may be slid out of the forward end of the receiver when 70 the gun is taken down.

Other modes of applying the principle of my invention may be employed for the mode herein explained. Change may therefore be 75 made as regards the mechanism thus disclosed, provided the principles of construction set forth, respectively, in the following claims are employed.

Having thus described my invention, what 80 I claim as new and desire to secure by Letters Patent, is:—

1. In an integral fire-arm, a receiver frame comprising a top and side-walls and having tangs at its rear end for attaching it 85 to the stock and a front wall formed with openings, a trigger and sear carrying frame detachably secured between said side-walls, a magazine tube having its rear end detachably secured in an opening in said front wall, and a barrel and extension slidable in the top of said frame and through said front wall and having a slidable connection upon 90 said magazine-tube.

2. In an integral fire-arm, a receiver frame comprising a top of substantially cylindrical outline and flat side-walls and having tangs at its rear end for attaching it to the stock and a forward wall formed with an arched upper opening and a screw-threaded lower opening, a trigger, carrier and sear carrying frame detachably secured between the rear portions of said side-walls in the open lower side of the same, a magazine tube having its rear screw-threaded end secured in the threaded opening of the front-wall of the receiver, a barrel-extension slidable in the top of the receiver, a barrel having its rear end secured to said extension, a collar-bracket secured to said barrel and 100 sliding upon said magazine-tube, and a coiled action-spring upon said tube and bearing against said collar-bracket to force 105 the same forward.

3. In a fire-arm, a receiver, a barrel 110 formed with a rearward extension slidable in said receiver and formed at the rear end of its edge with a cam-bulge, a breech-block slidable within the receiver and barrel extension and formed with a notch in its forward end, separate means connected to said barrel and block for automatically drawing them forward, and a locking bolt formed with a cam adapted to be engaged by said cam-bulge to be depressed by the same and 115 with a shoulder adapted to engage said notch and having a spring for forcing it upward.

4. In a fire-arm, a receiver, a barrel having an extension at its rear end slidable in said receiver and formed with a recess in 120

- the inner side of its top, a breech-block slide-
able in said receiver and extension and
formed with a longitudinal bore having an
enlargement opening to register with said
recess when the extension and block are in
their forward positions, a bolt rotatable in
said bore and provided with an eccentric
block in said enlargement capable of engag-
ing the recess in the extension and with a
projecting rear end having oblique flanges,
fingers projecting from the rear end of the
receiver to have their ends engage said
flanges to rotate the bolt, and a torsion
spring connected to rotate said bolt.
5. In a fire-arm, a receiver, a barrel hav-
ing an extension at its rear end slideable in
said receiver, a breech-block slideable in said
receiver and extension, a firing-pin slideable
in said block and formed with a shoulder, a
spring forcing said pin forward, a bolt rotat-
able in said block, and provided with a cam-lug
adapted to engage the shoulder of the
firing-pin and with a rearwardly pro-
jecting end having oblique flanges, fingers
projecting from the rear end of the receiver
to have their ends engage said flanges to
rotate the bolt, and a torsion spring connect-
ed to said bolt to rotate it in the opposite
direction.
10. In a fire-arm, a receiver having a car-
rier-chamber in its forward portion formed
with an open bottom, a magazine having its
discharge end opening into said chamber, a
barrel in said receiver, a longitudinally
slotted carrier-arm pivoted at its rear end
to tilt in said carrier-chamber, and a finger-
piece sliding in said slotted arm and formed
with a stop against which the head of a car-
tridge may bear, whereby a cartridge may
be manually inserted into the chamber of the
barrel.
15. In a fire-arm, a slideable breech-block,
a firing-pin slideable in said block and hav-
ing a spring for throwing it forward and
formed with a forwardly-facing shoulder
projecting at the under side of said breech-
block, a substantially vertically guided sear
formed with a sear-shoulder upon its upper
end for engaging the shoulder of the firing-
pin and a shoulder at its rear edge, a spring
bearing upward upon said sear, a trigger
having a spring for throwing its free pulling
end forward and a forwardly-extending arm
formed with a bore having a slot at its for-
ward end, a spring-actuated plunger in said
bore and formed with a nose at its forward
end to engage the rear shoulder of the sear
and with a web slideable in said slot, and a
rigid pin against which said web abuts.
20. In a fire-arm, a receiver, a barrel hav-
ing an extension slideable in said receiver,
a breech-block slideable in said receiver and
extension and formed with a notch at its rear
end, means for automatically drawing said exten-
sion forward, means for automatically moving
said breech-block forward, a magazine-tube enter-
ing the forward end of said receiver and having
means for feeding the cartridges rearward, a car-
rier in said receiver for feeding cartridges
to the barrel, a lever fulcrumed in the re-
ceiver and having an end formed with a cam-
surface projecting into the rear end of the
magazine tube, and a pawl arranged in the
path of the notch in the breech-block to en-
gage the same and connected to said lever
to be disengaged from said notch when the
cam-surface is engaged and actuated by a
cartridge in the end of the magazine.
25. In a fire-arm, a receiver, a barrel and
extension slideable in said receiver, a maga-
zine-tube having its rear end screwed into
said receiver, a fore-arm having its forward
portion fitted upon said tube, a collar bear-
ing against the forward end of said fore-
arm and having means for clamping it upon
the tube, a collar-bracket secured to the
barrel and slideable upon the magazine-tube,
an action-spring around said tube and bear-
ing against a flange upon the same and
against the collar-bracket, a follower and
spring within said tube, a plug closing the
outer end of said tube, and a finger-piece
slideable in said plug and adapted to be
laterally swung to engage said plug and
tube.
30. In a fire-arm, a receiver, a barrel hav-
ing an extension at its rear end slideable in
said receiver and said extension formed with
a recess in the inner side of its top and with
an oblique edge at its rear corner, a breech-
block slideable in said receiver and extension
and formed with a longitudinal bore having
an enlargement opening to register with said
recess when the extension and block are in
their forward positions, a bolt rotatable in
said bore and provided with an eccentric
block in said enlargement capable of engag-
ing the recess in the extension and formed
with an oblique shoulder and said bolt also
provided with a projecting rear end having
oblique flanges, fingers projecting from the
rear end of the receiver to have their ends
engage said flanges to rotate the bolt, and a
torsion spring connected to rotate said bolt.
35. In a fire-arm, a receiver, a barrel hav-
ing an extension at its rear end slideable in
said receiver, a breech-block slideable in said
receiver and extension, a firing-pin slideable
in said block and formed with a shoulder, a
spring forcing said pin forward, a bolt rotat-
able in said block, and provided with a cam-lug
adapted to engage the shoulder of the firing-
pin and with a rearwardly pro-
jecting end having oblique flanges, fingers
projecting from the rear end of the receiver
to have their ends engage said flanges to
rotate the bolt, and a torsion spring connect-
ed to said bolt to rotate it in the opposite
direction.
40. In a fire-arm, a receiver having a car-
rier-chamber in its forward portion formed
with an open bottom, a magazine having its
discharge end opening into said chamber, a
barrel in said receiver, a longitudinally
slotted carrier-arm pivoted at its rear end
to tilt in said carrier-chamber, and a finger-
piece sliding in said slotted arm and formed
with a stop against which the head of a car-
tridge may bear, whereby a cartridge may
be manually inserted into the chamber of the
barrel.
45. In a fire-arm, a slideable breech-block,
a firing-pin slideable in said block and hav-
ing a spring for throwing it forward and
formed with a forwardly-facing shoulder
projecting at the under side of said breech-
block, a substantially vertically guided sear
formed with a sear-shoulder upon its upper
end for engaging the shoulder of the firing-
pin and a shoulder at its rear edge, a spring
bearing upward upon said sear, a trigger
having a spring for throwing its free pulling
end forward and a forwardly-extending arm
formed with a bore having a slot at its for-
ward end, a spring-actuated plunger in said
bore and formed with a nose at its forward
end to engage the rear shoulder of the sear
and with a web slideable in said slot, and a
rigid pin against which said web abuts.
50. In a fire-arm, a receiver, a barrel hav-
ing an extension slideable in said receiver,
a breech-block slideable in said receiver and
extension and formed with a notch at its rear
end, means for automatically drawing said exten-
sion forward, means for automatically moving
said breech-block forward, a magazine-tube enter-
ing the forward end of said receiver and having
means for feeding the cartridges rearward, a car-
rier in said receiver for feeding cartridges
to the barrel, a lever fulcrumed in the re-
ceiver and having an end formed with a cam-
surface projecting into the rear end of the
magazine tube, and a pawl arranged in the
path of the notch in the breech-block to en-
gage the same and connected to said lever
to be disengaged from said notch when the
cam-surface is engaged and actuated by a
cartridge in the end of the magazine.
55. In a fire-arm, a receiver, a barrel and
extension slideable in said receiver, a maga-
zine-tube having its rear end screwed into
said receiver, a fore-arm having its forward
portion fitted upon said tube, a collar bear-
ing against the forward end of said fore-
arm and having means for clamping it upon
the tube, a collar-bracket secured to the
barrel and slideable upon the magazine-tube,
an action-spring around said tube and bear-
ing against a flange upon the same and
against the collar-bracket, a follower and
spring within said tube, a plug closing the
outer end of said tube, and a finger-piece
slideable in said plug and adapted to be
laterally swung to engage said plug and
tube.
60. In a fire-arm, a receiver, a barrel hav-
ing an extension at its rear end slideable in
said receiver, a breech-block slideable in said
receiver and extension and formed with a
notch at its rear end, means for automatically
drawing said extension forward, means for automatically moving
said breech-block forward, a magazine-tube enter-
ing the forward end of said receiver and having
means for feeding the cartridges rearward, a car-
rier in said receiver for feeding cartridges
to the barrel, a lever fulcrumed in the re-
ceiver and having an end formed with a cam-
surface projecting into the rear end of the
magazine tube, and a pawl arranged in the
path of the notch in the breech-block to en-
gage the same and connected to said lever
to be disengaged from said notch when the
cam-surface is engaged and actuated by a
cartridge in the end of the magazine.
65. In a fire-arm, a receiver, a barrel, a
magazine parallel with said barrel, a breech-

block slidable in said receiver and having means for automatically throwing it forward, a stop arranged to engage and hold said block when in its rearmost position, and 5 a lever fulcrumed in said receiver and having a cam at one end projecting into the rear end of the magazine to be engaged and

moved by the contents of the same, and connected at the other end to said stop to disengage the same when so moved.

HENRY B. FEBIGER.
